LIFTING TONGS

Alfred Petersen, Chicago, Ill.

Application April 8, 1943, Serial No. 482,277

8 Claims. (Cl. 294—8.5)

This invention relates to lifting tongs, and more particularly to a novel form of tongs for lifting cloth articles of various kinds out of hot liquids such as in a wash tub, to avoid soiling or injuring the operator's hands, and when desired, enable the placing of such articles into a wringer or the like, without the need of the operator's hand touching the articles.

As heretofore practiced, the lifting by hand of cloth or other articles out of the water in a wash tub upon completion of the wash, is an unpleasant task for many reasons, including getting the hands soiled with dirty water, burning or scalding the hands when the water is hot, injury to the fingers by pins or other sharp articles, as well as danger of injury to the fingers by getting them caught between the wringer rolls when inserting the articles being washed into the wringer.

By the present invention I have overcome the above objections by providing a pair of tongs (preferably of wood but not necessarily limited thereto) light in weight, and of novel construction to be efficient in use, durable, pleasing in appearance, economical to manufacture and easy to operate, so that the operator can place the separated free ends of the tongs in the water, close said ends together, and grasp the article or articles in the water, lift them out of the water and insert them into the wringer if desired. Should the forward ends of the tongs accidentally become caught in the wringer the tongs (being reasonably small in cross-section and free of projections) may pass through the wringer without damage either to the tongs, or the wringer, or the operator's hand.

Among the objects of my invention are to overcome the above objections and make possible the achievement of the above advantages.

Another object of my invention is to provide a novel form of pivotal connection between the two legs of the tongs.

A further object is to provide a novel form of plate and novel connection of the same to the tong arms to produce improved articulation between these arms.

A still further object is to provide a pair of tongs with light weight arms that normally stand apart and are so shaped and arranged that they may be readily grasped by one hand of the operator and be easily and effectively operated.

Other objects, advantages and capabilities will later more fully appear.

My invention further resides in the combination, construction and arrangement of parts illustrated in the accompanying drawing, and while I have shown therein a preferred embodiment, I wish it understood that the same is susceptible of modification and change without departing from the spirit of my invention.

In the drawing:

Fig. 1 is a side elevation of a pair of lifting tongs embodying my invention, the free ends of the tongs being shown in nearly closed position in dotted lines.

Fig. 2 is an edge elevation of the tongs shown in Fig. 1.

Fig. 3 is a fragmentary longitudinal section on the line 3—3 of Fig. 2.

Fig. 4 is a transverse section on the line 4—4 of Fig. 3.

Fig. 5 is a view similar to Fig. 3 but showing the parts in the position they will occupy when the tong arms are closed.

Referring more in detail to the drawing my improved tongs comprise the two arms 1 and 2, each formed at the jointed end with a centrally located longitudinal slot, this slot being designated in the arm 1 at 3, and in the arm 2 at 4. Formed in the arms 1 and 2 to pass transversely therethrough are holes 5 and 6, respectively. Floatably mounted within the slots 3 and 4 is a metal plate 7 having fixed centrally in one end portion, to extend approximately equal distances on each side, a pin 10 which in length is preferably substantially equal to the thickness of one of the arms. Plate 7 has also formed therein at equal distances from pin 10 and in transverse alignment therewith two holes 8 and 9 through which loosely extend the pins 11 and 12 respectively (see Figs. 3 and 4), which are fixed in holes 5 and 6 of the arms, holes 5 and 6 being in alignment with holes 8 and 9, respectively.

Pin 10 is preferably larger in diameter than pins 11 and 12 and of a diameter, and so located with relation to pins 11 and 12, and between the arms, that the outer cylindrical surface of pin 10 will form bearing surfaces for the adjacent inner faces of the arms 1 and 2 as said arms are opened and closed. Pins 11 and 12 are fixed in the holes 5 and 6 of the arms by riveting as shown in Fig. 4 or by a tight fit, or in any other manner desired. Also if desired the pins 11 and 12 may be loose in the holes 5 and 6 of the arms and tight in the plate 7, the main requirement being that pins 11 and 12 be tight in one of these parts and loose in the other to prevent the pins from falling out. If desired, however, these pins may be loose in both the plate and the arms if suitable means are provided to prevent falling out of the pins.

Except for the pins 11 and 12, and the bearing contact of the arms 1 and 2 upon the pin 10, the plate 7 is otherwise unconnected to the arms, but floats loosely in the slots 3 and 4 for edge-wise movement at its free end. This provides an entirely new type of floating pivotal mounting between a pair of tong arms such as those described herein. It is also to be noted that the

adjacent surfaces of the arms will have a rolling action with relation to the pin 10 which, in combination with the pins 11 and 12, adds greatly to the stability of the pivotal mounting, gives a greater freedom of movement between the arms, produces a greatly increased lifetime of usefulness of the tongs, eliminates protruding projections, enables a more convenient grasping of the tongs with the hand of the operator, creates a more pleasing appearance, and greatly enhances the saleability and usefulness of the tongs herein described.

In order to normally hold the arms 1 and 2 apart I have provided a coiled compression spring 13 the ends of which are respectively seated within the sockets or depressions 14 and 15 against the bottoms of which the spring constantly exerts an outward pressure. This continuously holds the arms apart except when they are forced together by the hand of the operator or otherwise as desired. Other forms of spring means for normally holding the arms apart may be used if preferred.

At their rear ends, each of the arms 1 and 2 are cut on an incline 16, which inclined portions face each other so as to form an abutment when the arms are held, by the spring 13, open to their maximum degree. In other words the inclined faces 16 limit the amount of opening movement the arms are permitted to have.

The inner faces of the free ends of the arms 1 and 2 are formed with serrations or roughened portions 17 to afford a better and more positive grip by the tong ends on an article being picked up or handled, which is of especial value when handling wet or slippery articles.

As will be understood the adjacent faces of the arms will have a combined rolling and sliding movement upon the pin 10, the free end of the plate 7 being free to move or float edgewise in the slots 3 as the direction of application of pressure upon the arms and upon pins 11 and 12 may require in the various movements of the tongs during operation. When pressure is applied upon the arms, the arms will bear against the large pin 10 rather than upon the smaller pins 11 and 12, the latter serving to prevent the parts from falling apart. The plate 7 in the slots holds the arms in alignment and prevents twisting or distortion of the arms. The plate floats in the slots and thus accommodate itself to the movements of the arms. Also the operator cannot get a finger between the arms and close the arms, hence it is impossible for the operator to have his fingers drawn into a wringer should the tongs be accidentally pulled thereinto.

Having described my invention, I claim:

1. In lifting tongs, a pair of arms, means for pivotally connecting the arms together, said means comprising a plate, a pin in each of said arms passing through the plate, and a third pin in the plate extending laterally therefrom and positioned between adjacent faces of the inner edge of the two arms, said third pin being positioned between the other two pins in a direction laterally of the arms.

2. In lifting tongs, a pair of pivotal arms, each of the arms having a transverse slot in its rear end portion, a plate in said slots, a pin in each of the arms and passing through the plate, a third pin extending laterally from the plate and

between the inner edges of the arms, said inner edges having a combined rolling and longitudinal sliding movement upon said third pin, and spring means for normally urging the arms apart at their free ends, said third pin being positioned laterally between the other two pins.

3. In lifting tongs, a pair of pivotal arms, each of the arms having a transverse slot in its rear end portion, a plate in said slots, a pin in each of the arms and passing through the plate, a third pin extending laterally from the plate and between the inner edges of the arms, said inner edges having a combined rolling and sliding movement upon said third pin, and spring means for normally urging the arms apart at their free ends, said three pins being in lateral alignment.

4. In lifting tongs, a pair of pivotal arms, a plate, each of the two arms being pivotally connected to the plate, and a pin extending from the plate into the space between the inner edges of the arms, and spring means normally urging the arms to swing apart, said pin being positioned laterally between the means pivotally connecting the two arms to the plate.

5. In lifting tongs, a pair of pivotal arms, a plate, each of the two arms being pivotally connected to the plate, and a pin extending from the plate into the space between the inner edges of the arms, and spring means normally urging the arms to swing apart, and stop means for limiting the amount of said outward swinging movement, said pin being positioned laterally between the means pivotally connecting the two arms to the plate.

6. In lifting tongs, a pair of pivotal arms, a plate, each of the two arms being pivotally connected to the plate, and a pin extending from the plate into the space between the inner edges of the arms, and spring means normally urging the arms to swing apart, and stop means for limiting the amount of said outward swinging movement, said last mentioned means comprising an inclined face on the rear end of each of the arms, said pin being positioned laterally between the means pivotally connecting the two arms to the plate.

7. In lifting tongs, a pair of swingable arms, a plate at the rear end of said arms, three pins passing through the plate, one of said pins passing into one of the arms, another of the pins passing into the other of the arms, and the third pin being positioned between the inner edges of the two arms to have a combined rolling and sliding movement thereon, said three pins being in lateral alignment and falling in a straight line passing laterally therethrough and extending substantially at right angles to the longitudinal axis of each of the arms when the arms are closed.

8. In lifting tongs, a pair of swingable arms, a plate at the rear end of said arms, three pins passing through the plate, one of said pins passing into one of the arms, another of the pins passing into the other of the arms, and the third pin being positioned between the inner edges of the two arms so that said inner edges have a combined rolling and longitudinal sliding movement thereon, each of said arms having a slot floatably receiving the plate, and said third pin being positioned laterally between the other two pins.

ALFRED PETERSEN.
